ARTICLE CARRIER

Homer W. Forrer, Atlanta, Ga., assignor to The Mead Corporation, a corporation of Ohio
Filed May 15, 1962, Ser. No. 194,810
4 Claims. (Cl. 220—113)

This invention relates to article carriers and more particularly to bottle carriers of the collapsible type which are commonly constructed of paperboard.

In carriers of this type, it is common practice to provide a locking notch in one or both ends of the bottom panel and to arrange for this notch to engage a co-operating notch formed in a pair of vertically disposed riser panels which are integrally formed with the handle of the carrier and which are foldably joined respectively to the adjacent end panels of the carrier on each side of the handle. Such a construction is merely for the purpose of holding the carrier in set-up condition and necessarily requires the use of a certain amount of paperboard in order to provide an adequate locking arrangement.

A principal object of this invention is to provide an improved locking arrangement for an article carrier which requires a minimum of paperboard.

The invention in one form as applied to an article carrier having side and end wall panels and a bottom panel comprises a pair of riser panels foldably joined respectively to the inner edge of the end panels at one end of the carrier, a locking tab struck out of at least one of the riser panels and folded downwardly, and a locking notch formed in the locking tab and disposed at a level to engage one end of the bottom panel thereby to hold the carrier in set-up condition.

For a better understanding of the invention reference may be had to the following detailed description taken in conjunction with the accompanying drawings in which FIG. 1 is a perspective view of a carrier embodying the invention; FIG. 2 is a side view of the carrier depicted in FIG. 1; FIG. 3 is an end view of the carrier depicted in FIG. 1; FIG. 4 is a plan view of a blank from which a carrier is formed according to this invention; and in which FIGS. 5-8 inclusive depict progressive stages through which the blank of FIG. 4 is passed in forming a carrier according to this invention.

With reference to the drawings and particularly with reference to FIGS. 1 and 4, the numerals 1 and 2 designate side walls of the carrier while the numerals 3, 4, 5 and 6 denote end panels. End panels 3 and 4 are foldably connected with side wall 1 along fold lines 7 and 8 respectively while end panels 5 and 6 are foldably connected with side wall 2 along fold lines 9 and 10 respectively. Foldably joined to the bottom edge 11 of side wall 1 is a bottom panel generally designated by the numeral 12 and which is provided with a medial fold line 13. Bottom panel 12 is foldably joined along the fold line 14 to the side panel 2. A notch 16 is formed in bottom panel 12 at one end of medial line 13. Foldably joined along the fold line 16 to the end panel 3 is a riser panel in the form of medial partitioning support element 17. Similarly, riser panels in the form of medial partitioning support elements 18, 19 and 20 are foldably joined along lines 21, 22 and 23 to the end panels 5, 6 and 4, respectively.

The handle structure of the carton depicted in FIG.

2

4 is similar to that disclosed and claimed in Patent 2,537,452 and comprises two pairs of telescopically arranged panels designated in FIG. 4 by the numerals 24, 25, 26 and 27. The panels 24-27 are generally similar in their overall arrangement and, therefore, only one of such panels will be described in detail, it being deemed desirable to point out, however, that the handle panel 24 is foldably joined to the handle panel 26 along the medial fold line 28 while the handle panel 25 is foldably joined to the handle panel 27 along the coincidental fold line 29. Panel 24 is separated from panel 25 along a cut line 30 while panel 26 is separated from panel 27 along a cut line 31 which coincides with line 30. The panel 24 may be defined by the points A, B, C, D, E and F so that the area enclosed by the lines connecting these points A-F defines the one handle panel 24 which is disposed in a flat plane. Line A—B is a cut line separating handle panel 24 from end panel 3. Similarly, line C—D is a cut line separating partitioning strip 32 from an edge of handle panel 24 while line D—E is a cut line coinciding with line 30 which separates panel 24 from panel 25. B—C is a fold line whereby the partitioning strip 32 is foldably connected with handle panel 24 while line G—H is a fold line along which the partitioning strip 32 is foldably joined with the side wall 2.

For the purpose of enabling the carrier to be readily grasped by the hand of the person carrying it, a pair of apertures 33 and 34 are provided in handle panel 24.

In similar fashion hand hold apertures 36 and 37 are provided in handle panel 25 and hand hold apertures 38 and 39 are provided in handle panel 27. Flaps 36A, 37A, 38A and 39A may be provided if desired, such elements being well known as cushioning elements.

As is disclosed in my above mentioned Patent 2,537,452, additional partitioning strips 40, 41 and 42 are provided and are interrelated with the other elements as described in detail above in connection with partitioning strip 32.

The panel elements 24 and 25 are telescoped over panel elements 25 and 27 when the carton is formed as will be described in detail hereinafter.

An auxiliary panel is provided in one of the handle panels, such as 26, instead of the hand gripping flaps designated 36A, 37A, 38A and 39A in connection with panels 24, 25 and 27. Such auxiliary panel is designated in the drawings by the numeral 43 and is separated from handle panel 26 along a cut line extending from the point designated I to point J and thence to points K and L. A perforated fold line designated by the numeral 44 is provided whereby the auxiliary panel 43 may be folded downwardly.

In accordance with this invention and for the purpose of interconnecting bottom panel 12 with riser panels 17 and 18 to hold the carrier erect, a locking tab 45 is struck out of riser panel 18 and is foldably joined thereto along line 45. When folded downwardly notch 47 in locking tab 45 engages notch 16 in bottom panel 12. While only one locking tab is shown in the drawings it will be understood that a tab similar to tab 45 could be struck out of panel 17 and if desired out of panels 19 and 20.

The first folding operation in forming the carrier from the blank depicted in FIG. 4 is shown in FIG. 5 and is performed after glue is applied to the blank as indicated by stippling in FIG. 4.

Such a folding operation causes the end panels 3 and 5 to swing over the side panels 1 and 2 along the fold lines 7 and 9, respectively. Simultaneously, partitioning strip 32 swings over along the top center portion 1A of side panel 1 along the fold line G—H. The partitioning strip 41 folds similarly. Since A—B is a cut line and B—C is a fold line, the above described folding operation causes the handle panel 24 to overlap the strip 32 partially as depicted in FIG. 5. In similar fashion the corresponding end panel 5 and handle panel 26 are simultaneously folded over, it being understood that the opening 33 coincides generally with the hand gripping opening 36 and the auxiliary panel 43 overlies and generally coincides with the hand gripping apertures 38 and 39. The inner ends of panels 17 and 18 are secured to panels 26 and 24, respectively, adjacent the fold lines 16 and 21 by glue indicated by stippled areas in FIG. 4. Glue as indicated by stippling in FIG. 4 on panels 25 and 27 holds these parts in place as depicted in FIG. 5. Thereafter an application of glue is made as indicated by the stippled areas in FIG. 5.

The next operation is depicted in FIG. 6 and is effected by simply folding the medial support riser elements 19 and 20 over onto handle panels 27 and 25 along their fold lines 22 and 23, respectively, and are secured thereto. This step also comprises folding the auxiliary panel 43 downwardly along the fold line 44, it being understood that the auxiliary panel 43 is maintained in the downwardly folded position due to glue indicated by stippling in FIG. 5. When so folded, the auxiliary panel 43 is disposed at the approximate level of the partition strips 32, 40, 41 and 42, as will be apparent from FIGS. 1 and 6. In addition panel 45 is folded downwardly along fold line 46 and is secured there by glue depicted in FIG. 5. Thereafter an application of glue indicated by stippling is made to the structure as shown in FIG. 6 and subsequently the arrangement is folded along the medial fold lines 28 and 29 to the position indicated in FIG. 7.

The final step in forming the carrier comprises the application of glue as indicated by stippled areas in FIG. 7 and the subsequent folding of side panel 1C and the adjoining side of bottom panel 12 along medial line 13 so that panel 1C is secured to side wall panel 1B of the side wall 1. The carrier then appears as depicted in FIG. 8 in finished but collapsed condition.

In order to set the carrier up from the collapsed condition of FIG. 8 to the condition depicted in FIG. 1, the side panels 1 and 2 are drawn apart while the handle panels are moved toward the left as viewed in FIG. 8. Simultaneously the bottom panel 12 is flattened out as the medial fold line 13 is moved upwardly. The notches 47 and 16 then come into engagement and serve to hold the carrier erect.

While I have shown and described a particular embodiment of the invention, I do not wish to be limited thereto and intend in the appended claims to cover all such changes and modifications as fall within the true spirit and scope of the invention.

What I claim as new and desire to secure by Letters Patent of the United States is:

1. An article carrier comprising a pair of handle panels foldably joined together along a medial fold line, a pair of riser panels foldably joined respectively to said handle panels along substantially coincidental fold lines disposed at the ends of said handle panels and generally normal to said medial fold line, a locking tab struck out of at least one of said riser panels and foldably joined thereto along a fold line spaced from said medial fold line and disposed so as to accommodate folding of said locking tab out of said riser panel and in a direction away from said medial fold line to a position of generally parallel face contacting relation therewith so as to form a downwardly protruding extension of said one riser panel, means for maintaining said locking tab in its folded position, and a locking notch formed on an edge of said

locking tab which is remote from the adjacent one of said coincidental fold lines and said locking notch being remote from the fold line which joins said locking tab to the riser panel from which said locking tab is struck.

2. An article carrier comprising a pair of handle panels foldably joined together along a medial fold line, a pair of riser panels foldably joined respectively to said handle panels along substantially coincidental fold lines disposed at the ends of said handle panels and generally normal to said medial fold line, a locking tab struck out of one of said riser panels and foldably joined thereto along a fold line spaced from said medial fold line and disposed so as to accommodate folding of said locking tab out of said riser panel and in a direction away from said medial fold line to a position of generally parallel face contacting relation therewith, means for maintaining said locking tab in its folded position, a pair of end panels foldably joined respectively to said riser panels along said coincidental fold lines along portions thereof which are remote from said medial fold line, a pair of side wall panels foldably joined respectively to said end panels along fold lines which are spaced from and generally parallel to said coincidental fold lines, said one riser panel and its associated end panel extending a substantially shorter distance from said medial fold line than the bottom edge of the associated one of said side walls, the length of said locking tab being such that the end thereof remote from said medial fold line is approximately the same distance therefrom as is the bottom edge of said one side wall.

3. An article carrier comprising a pair of handle panels foldably joined together along a medial fold line, a pair of riser panels foldably joined respectively to said handle panels along substantially coincidental fold lines disposed at the ends of said handle panels and generally normal to said medial fold line, a locking tab struck out of one of said riser panels and foldably joined thereto along a fold line spaced from said medial fold line and disposed so as to accommodate folding of said locking tab out of said riser panel and in a direction away from said medial fold line to a position of generally parallel face contacting relation therewith, means for maintaining said locking tab in its folded position, a pair of end panels foldably joined respectively to said riser panels along said coincidental fold lines at portions thereof which are remote from said medial fold line, a pair of side wall panels foldably joined respectively to said end panels along fold lines which are spaced from and generally parallel to said coincidental fold lines, said one riser panel and its associated end panel extending a substantially shorter distance from said medial fold line than the bottom edge of the associated one of said side walls, the length of said locking tab being such that the end thereof remote from said medial fold line is approximately the same distance therefrom as is the bottom edge of said one side wall, a bottom panel foldably joined to said bottom edge of said one side wall, and a side wall panel foldably joined to the edge of said bottom wall which is remote from said one side wall.

4. An article carrier comprising a pair of handle panels foldably joined together along a medial fold line, a pair of riser panels foldably joined respectively to said handle panels along substantially coincidental fold lines disposed at the ends of said handle panels and generally normal to said medial fold line, a locking tab struck out of one of said riser panels and foldably joined thereto along a fold line spaced from said medial fold line and disposed so as to accommodate folding of said locking tab out of said riser panel and in a direction away from said medial fold line to a position of generally parallel face contacting relation therewith, means for maintaining said locking tab in its folded position, a pair of end panels foldably joined respectively to said riser panels along said coincidental fold lines at portions thereof which are remote from said medial fold line, a pair of

side wall panels foldably joined respectively to said end panels along fold lines which are remote from the fold lines between said end panels and said riser panels, said one riser panel and its associated end panel extending a substantially shorter distance from said medial fold line than the bottom edge of the associated one of said side walls, the length of said locking tab being such that the end thereof remote from said medial fold line is approximately the same distance therefrom as is the bottom edge of said one side wall, the other of said side wall 10

panels extending from said medial fold line a distance which is generally equivalent to the extent of said riser panels in a direction away from said medial fold line.
